PULSE RATE INDICATOR FOR BODY FUNCTIONS

Carl A. Budde, Los Angeles County, Calif.
(8427 Balboa Blvd., Northridge, Calif. 91324)

Filed Apr. 17, 1967, Ser. No. 6,722

Term of patent 14 years

(Cl. D83—1)

Figure 1

Figure 2

Figure 3

FIGURE 1 is a top view of a pulse rate indicator for body functions showing my new design;

FIGURE 2 is a front view thereof; and

FIGURE 3 is a right side view thereof.

The surfaces not shown are plain and unornamented.

I claim:

The ornamental design for a pulse rate indicator for body functions, substantially as shown and described.
